UNITED STATES PATENT OFFICE

GEORGE F. ZEALAND, OF PHILADELPHIA, PENNSYLVANIA, ASSIGNEE OF FORTY-NINE
ONE-HUNDREDTHS TO SAMUEL W. FALES, OF PHILADELPHIA, PENNSYLVANIA

MESSAGE-DISPLAYING DEVICE

Application filed December 24, 1926. Serial No. 156,939.

The principal object of my invention is to provide a device for displaying messages in public places, such as railroad stations, hotel lobbies, theatre lobbies, etc., and which is accessible for use by the general public.

As an illustration of the utility of the device, should two parties have a mutual appointment to meet at a railroad station in order to board a certain train, and one of the parties should fail to keep the appointment, the other party upon arrival at the railroad station could leave a message to be read by the tardy one. Such message could be addressed to the party who had failed to keep the appointment; and state that the other party had boarded the train and would meet the second party at their common point of destination.

The device is adapted to be operated by a coin being inserted in a coin slot located in the face of the device and subsequent manipulation of a control lever which opens a door located in the front wall of the device. The message can then be written on a card provided for the purpose, and the door of the device thereafter closed, and automatically locked, so that the message thereafter cannot be tampered with.

The device is so constructed that a coin having been placed in the coin slot thereof and the operating lever subsequently manipulated effects the sealing of the coin slot in such a manner that no additional coin can be placed therein, until such time as an authorized attendant removes the first coin, clears the device of the message which had been previously placed therein; and by so doing the device is automatically reset to receive another message.

The detailed construction of my invention will be fully disclosed hereinafter, reference being had to the accompanying drawings, of which:

Fig. 1 is a perspective view of a single

structure constructed in accordance with the principles of my invention;

Fig. 2 is a sectional plan view taken along the line 2—2 of Fig. 1;

Fig. 3 is a transverse sectional elevation taken along the line 3—3 of Fig. 2;

Fig. 4 is a sectional elevation taken along the line 4—4 of Fig. 2;

Figs. 5, 6 and 7 are detached perspective views of certain details of the invention;

Fig. 8 is a front elevation of a bank of the devices, such as would be placed in public places; and

Fig. 9 is a rear elevation illustrating the means of locking the devices of the entire bank, to prevent the removal of inserted coins by other than the authorized attendant.

My device comprises a box-like structure 1, constructed in any suitable manner, and having a door 2 hinged in the front wall of the box 1. The door 2 is provided with a suitable transparent panel 3, through which a message display card 4 is visible. The card 4 is supported between the rear face of the door and the front face of a fixed partition 5, which is suitably mounted in the box 1. The door 2 is provided with a spring latch 10 having a shoulder 9 adapted to engage a flange 11 which extends laterally from a vertically disposed segmental locking plate 12. The segmental locking plate is pivotally mounted in a cavity 13 formed between rigid transverse partitions 14 and 15 in the box 1. The pivot pin 16 of the segmental locking plate 12 extends between the said partitions and is rigidly secured therein.

The partition 14 is provided with an arcuate slot 17 through which the lateral flange 11 of the locking plate 12 extends, and is of such proportions as to permit a limited oscillatory movement of the plate 12 and its flange 11. The flange 11 is provided with an opening 19 intermediate its ends for purposes hereinafter described.

The segmental locking plate 12 is provided

with an arcuate slot 20, through which and the partitions 14 and 15 a limiting pin 21 extends. A spring 22 is coiled around the pivot pin 16, and has one arm 23 engaging one part of the lateral flange 11 of the segmental locking plate 12, and its other arm 24 secured to a pin 25 which extends laterally from the partition 14. The spring 22 normally maintains the segmental locking plate 12 in the position illustrated in Fig. 3.

A coin slot 26 is formed in the upper portion of the cavity 13 between the upper wall 27 of said cavity and a straight edge 28 of the segmental plate 12. A filling plate 29 is also positioned in the cavity, the upper edge 30 of said filling plate being substantially aligned with the straight edge 28 of the locking plate 12, to form the lower wall of the coin slot 26. The rear wall of the cavity 13 is provided by a bar 31, which is pivoted at 32 between the partitions 14 and 15, and has its lower edge 33 bevelled in a plane coincident with an angularly disposed coin discharge edge 34 of the filling plate 29.

A second cavity 35 is formed in the box 1 adjacent the previously mentioned cavity 13, and in which is mounted an operating lever 36 which extends through a slot 37 to the front face of the box 1 and is provided with a finger pad 38 adjacent thereto. The lever 36 is pivoted on a pin 39 which extends between and is secured in the partition 15 and the end wall 40 of the box 1. A second lever 41 is mounted in the cavity 35 above the lever 36, and is connected thereto by means of links 42 pivoted at its respective ends to the levers 36 and 41. The lever 41 is pivoted on a pin 42 extending between and secured to the partition 15 and end wall 40. A spring 43 has one of its ends attached to the lever 36 and its opposite end secured to a pin 44 extending between the partition 15 and the end wall 40, which tends to normally maintain the lever 36 in a raised position and in engagement with the upper end of the slot 37. The lever 41 is provided with a laterally extending lug 45 which projects through a slot 46 formed in the partition 15.

The upper wall 27 of the coin slot 26 is recessed at 47 in order that the lower side 48 of the lug 45 will lie in a plane coincident with the plane of the upper wall 27 of the coin slot 26. As shown in Fig. 3, the coin slot 26 is formed at an angle relative to the horizontal, to provide an inclined run for the coin α , to insure the coin, after insertion in the slot 26, of passing to the rear of the said coin slot and engaging the bar 31.

As shown in Fig. 4, the partition 5 is provided with an opening 50 through which the spring latch 10 projects, and a second slot or opening 51 through which a flat spring 52 projects. The spring 52 has one end secured to the bottom wall of the box 1, the opposite end of the spring being provided with a

curved portion 53 which engages the rear face of the door 2 for purposes hereinafter described.

As shown in Fig. 9, a series of boxes 1 are suitably secured together to form a bank. Extending longitudinally of each tier of boxes 1 is a locking bar 55 which is slidably mounted in a guide channel member 56 secured to the rear walls of the boxes 1. The locking bars 55 normally overlap the lower end of each of the bars 31, as shown in Fig. 3, and prevent the said bars from being swung on their pivots to release any coins which have been inserted in their respective boxes 1.

The bars 55 are provided with notches 57 which are adapted to be aligned with the bars 31 when the locking bars 55 are moved longitudinally with respect to the guide channel 56, which are also provided with notches 58 in alignment with the bars 31. Each of the bars 55 is provided adjacent one of its ends with a notch 59 having a vertical wall adapted to be engaged by the vertical wall of a locking lug 60 which extends laterally from a bar 61. The bar 61 is slidably mounted in a guide channel 62 and is adapted to be moved vertically relative thereto, to release the bars 55 in order that they may be moved longitudinally. Adjacent its lower end the vertical bar 61 is provided with an eye 63 which extends through a slot 64 in the guide channel 62. An ordinary hasp leaf 65 is pivoted to the bank of the boxes 1 adjacent the lower end of the vertical bar 61, and is provided with the usual slot through which the eye 63 projects. The shackle of a padlock 66 passes through the eye 63 in the usual manner thereby maintaining the hasp in position on the eye 63, which in turn prevents vertical movement of the bar 61.

In operation, assuming that the various boxes 1 have been serviced by an authorized attendant, a coin α may be inserted in any of the coin slots 26. The coin will pass down the incline face 28-30, of the segmental locking plate 12 and the filling plate 29 respectively, to the position illustrated in full lines in Fig. 3, adjacent the coin delivery bar 31.

By applying pressure to the upper face of the finger pad 38, the lever 36 will be turned on its pivot 39 and through the links 42 will turn the lever 41 on its pivot 42, causing the under surface 48 of the laterally extending lug 45 to engage the top edge of the coin α . Continued pressure on the pad 38 will cause the coin α to be moved downwardly in a path parallel to the bar 31, thereby turning the segmental locking plate 12 on its pivot 16, the same being moved from its full line position in Fig. 3 to the position illustrated in broken lines in said figure, the coin α passing downward to the position illustrated in broken lines in said figure, resting upon the inclined surface 34 of the filling plate 29 and

between the inner edge of the bar 31 and the straight edge 28 of the segmental locking plate 12. Thus it will be seen that the coin in this position maintains the said locking plate 12 in such a position that additional coins cannot be inserted within the coin slot 26.

When the pressure is relieved from the finger pad 38, the levers 36 and 41 will be returned to their normal inoperative positions by the spring 43. The lower edge of the slot 46 is positioned in such a manner, relative to the upper edge 28 of the segmental locking plate 12, that the said plate can only be operated when a coin is placed in the coin slot 26.

As the segmental plate 12 is rotated from its full line position shown in Fig. 3 to its broken line position in said figure, the integral laterally extending flange 11 of said plate is likewise rotated, and as the opening 19 in said flange passes the spring latch 10 of the door 2 the flat spring 52 causes the door to be swung on its pivots and the shoulder 9 of the said spring latch to pass outward, through the opening 19 in the locking flange 11. The door 2 is now open, and the card 4 is exposed in such a manner that a suitable message may be written thereon. If desired, a pencil Y may be placed in the box 1, as illustrated in Fig. 4, for the convenience of the person writing the message.

Upon completion of the message, the door is closed and the shoulder 9 of the spring latch 10 assumes a position to the rear of the flange 11, thereby locking the door 2 which cannot be reopened until such time as the coin x is removed from the box 1. Such removal is effected by an authorized attendant at a convenient time during the day or night. By unlocking the padlock 66, the shackle thereof may be removed from the eye 63 and the hasp leaf 65 subsequently removed from the eye 63 which will permit of the bar 61 being moved vertically in the guide 62, the locking lugs 60 thereby being moved out of the notches 59 of the horizontally extending bars 55. The bars 55 may then be moved longitudinally until the notches 57 thereof are aligned with the coin release bars 31, and the notches 58 formed in the guide channels 56. The bars 31 may then be swung on their pivots 32 and the coin x removed from the box 1. The spring 22 will then turn the locking plate 12 on its pivot from the position shown in broken lines in Fig. 3 to that illustrated in full lines in said figure.

As the opening 19 in the locking flange 11 of said plate again passes the shoulder 9 of the spring latch 10, the spring 52 will move the door 2 to its open position. After the coins have been removed and the several bars 55 restored to their locking positions as shown in Fig. 8, the bar 61 lowered until the lugs 60 thereof again engage the notches 59

of the bars 55 and the hasp and padlock are restored to their locking positions, the attendant will remove the cards 4 upon which messages had been written and replace them with fresh cards, after which he will close each of the doors 2. The servicing of the bank of message display devices is then complete and they are ready to receive new messages.

From the above description, it will be obvious that I provide a device by which individuals may display messages addressed to other individuals in such public places as the general public are in the habit of using as the designated points of meeting in making appointments, thus avoiding the necessity of one person being inconvenienced by having to wait after the appointed time for persons who are tardy in keeping appointments. Crowding and confusion can thus be avoided in such places as theatre lobbies. The person first arriving, if an appointment has been made with a second party, may, by employing my device, deposit the theatre seat check for the second party at the box office of the theatre and display a message for the said second party stating the condition, thus crowding and confusion in the theatre lobby may be avoided.

While I have shown one method and apparatus for effecting the object desired, I do not intend that such illustration may be construed as limiting the scope of the invention as various modifications may be made in the device without departing from the essential spirit of the invention, that of the display of messages in public places by one individual addressed to another individual. I, therefore, desire that only such limitations be placed upon the scope of the invention as are set forth in the appended claims, or found necessary by the prior art of record.

I claim:

1. A message displaying device comprising a casing, an element in said casing adapted to receive the message to be displayed; a transparent movable element in said casing providing access to said message receiving element, and through which the message receiving element may be viewed; a rotatable locking element; a lateral flange on and extending substantially perpendicular to the general plane of said locking element; a spring latch on said movable element engaging said lateral flange; a straight side formed on said locking element; a coin slot formed in said casing between the said straight side of said locking element and one wall of said casing; and operating mechanism for said locking element adapted to engage a coin inserted in said slot.

2. A message displaying device comprising a casing, an element in said casing adapted to receive the message to be displayed; a transparent movable element in

said casing providing access to said message receiving element, and through which the message receiving element may be viewed; a rotatable locking element; a lateral flange on and extending substantially perpendicular to the general plane of said locking element; a spring latch on said movable element engaging said lateral flange; a straight side formed on said locking element; a coin slot formed in said casing between the said straight side of said locking element and one wall of said casing; and operating mechanism for said locking element adapted to engage a coin inserted in said slot at one side of the center of rotation of said locking element, whereby the said locking element is adapted to rotate to release said movable element and to seal said coin slot.

3. A message displaying device comprising a casing, an element in said casing adapted to receive the message to be displayed; a transparent movable element in said casing providing access to said message receiving element, and through which the message receiving element may be viewed; a rotatable locking element; a lateral flange on and extending substantially perpendicular to the general plane of said locking element; a spring latch on said movable element engaging said lateral flange; a latch release opening formed in said lateral flange intermediate its ends; a straight side formed on said locking element; a coin slot formed in said casing between the said straight side of said locking element and one wall of said casing; and operating mechanism for said locking element adapted to engage a coin inserted in said slot at one side of the center of rotation of said locking element, whereby the said locking element is adapted to rotate to release said movable element and to seal said coin slot.

4. A message displaying device comprising a casing, an element in said casing adapted to receive the message to be displayed; a transparent movable element in said casing providing access to said message receiving element, and through which the message receiving element may be viewed; a rotatable locking element; a lateral flange on said locking element; a spring latch on said movable element engaging said lateral flange; a latch release opening formed in said lateral flange intermediate its ends; a straight side formed on said locking element; a coin slot formed in said casing between the said straight side of said locking element and one wall of said casing; and operating mechanism for said locking element adapted to engage a coin inserted in said slot at one side of the center of rotation of said locking element, whereby the said locking element is adapted to rotate to release said movable element and to seal said coin slot; and means for forcing said latch

through said release opening, when the locking element is rotated.

5. A message displaying device comprising a casing; a transparent door hinged to said casing; a partition in said casing parallel to said door; a message card between said door and said partition; a rotatable locking element in said casing; a lateral flange on said locking element; a spring latch on said door engaging said flange; a latch release opening in said flange; operating mechanism for said rotatable locking member; and a slot formed between said locking element and its operating mechanism for the reception of an intermediate connecting element.

6. A message displaying device comprising a casing; a transparent door hinged to said casing; a rotatable locking element in said casing; a lateral flange on and extending substantially perpendicular to the general plane of said locking element having an opening intermediate its ends; a spring latch on said door adapted to engage said flange at one side of said opening; operating mechanism for said rotatable locking element; a coin slot formed in said casing and adapted to guide a coin between said rotatable locking element and the operating mechanism therefor, whereby said locking element may be rotated relative to said spring latch permitting the said latch to pass through said flange opening to release the door, and to bring the portion of the flange at the opposite side of said opening into position to be engaged by the spring latch to relock said door when the door is again closed, said rotatable locking element functioning as a means to completely close said coin slot against the insertion of means designed to unlock the door while the operating coin remains in the device, for the protection of the message contained in the device.

7. A message displaying device comprising a casing; a transparent door hinged to said casing; a rotatable locking element in said casing; a lateral flange on and extending substantially perpendicular to the general plane of said locking element having an opening intermediate its ends; a spring latch on said door adapted to engage said flange at one side of said opening; operating mechanism for said rotatable locking element; a coin slot formed in said casing and adapted to guide a coin between said rotatable locking element and the operating mechanism therefor, whereby said locking element may be rotated relative to said spring latch permitting the said latch to pass through said flange opening to release the door, and to bring the portion of the flange at the opposite side of said opening into position to be engaged by the spring latch to relock said door when the door is again closed.

closed, said rotatable locking element functioning as a means to completely close said coin slot against the insertion of means designed to unlock the door while the operating coin remains in the device, for the protection of the message contained in the device; means for permitting the removal of the operating coin from the casing; and means for returning the rotatable locking element to its normal position when the operating coin is removed, whereby the door is automatically opened to permit removal of the message contained in the device.
